(57) **CLAIM**

The ornamental design for a LED light fixture, as shown and described.

DESCRIPTION

FIG. 1 is a perspective view of the LED light fixture.

FIG. 2 is a front view of the LED light fixture.

FIG. 3 is a rear view of the LED light fixture.

FIG. 4 is a left side view of the LED light fixture.

FIG. 5 is a right side view of the LED light fixture.

FIG. 6 is a top plan view of the LED light fixture.

FIG. 7 is a bottom plan view of the LED light fixture; and, FIG. 8 is a reference view of the LED light fixture in which two heat sinking fins are separated from the body of the lamp in order to show clearly an interior configuration shape of heat sinking fins.

The broken lines are directed to environment and are for illustrative purposes only. Thus, the broken lines form no part of the claimed design.
